ICE CREAM SCOOP

Richard I. Page, Minneapolis, Minn., assignor to Foley Manufacturing Company, Minneapolis, Minn., a corporation of Minnesota

Filed Jan. 25, 1967, Ser. No. 5,559

Term of patent 14 years

(Cl. D44—29)

FIG. 1

FIG. 2

FIG. 3

FIG. 4

FIG. 5

FIG. 6

FIG. 1 is a view in top plan of an ice cream scoop showing my new design;

FIG. 2 is a view in side elevation;

FIG. 3 is a view in bottom plan;

FIG. 4 is a longitudinal section taken on the line 4—4 of FIG. 1; and

FIGS. 5 and 6 are enlarged transverse sections taken on the lines 5—5 and 6—6 respectively of FIG. 2.

I claim:

The ornamental design for an ice cream scoop, as shown.
